CLAIM

The ornamental design for illuminated rear lights of motor vehicle as shown and described.

DESCRIPTION

FIG. 1 shows an elevation view of illuminated rear lights of motor vehicle according to a first embodiment of the design; FIG. 2 shows an elevation view of illuminated rear lights of motor vehicle according to a second embodiment of the design; and,

FIG. 3 shows an elevation view of illuminated rear lights of motor vehicle according to a third embodiment of the design.

The cross-hatched shading in the drawings represents illumination of the illuminated rear lights of motor vehicle. The illumination is not limited to any particular color or color combination. The vertical cross-hatched shading represents a first intensity of the illumination, whereas the combined vertical and horizontal cross-hatched shading represents a second intensity of the illumination that is greater than the first intensity of the illumination.

The broken lines illustrate portions of the motor vehicle that form no part of the claimed design.

The text PORSCHE forming part of the claimed design is a registered trademark of Dr. Ing. h.c. F. Porsche Aktiengesellschaft.
